United States Patent Office

Des. 204,367
Patented Apr. 12, 1966

204,367

VACUUM CLEANER

Arthur M. McGuire, Upper Darby, Pa., assignor of
one-half to Ralph H. Henshaw, Philadelphia, Pa.

Filed Sept. 29, 1965, Ser. No. 87,220

Term of patent 14 years

(Cl. D9—2)

FIG. 1.

FIG. 2.

FIG. 3.

FIG. 4.

FIG. 5.

FIG. 6.

FIG. 1 is a front view in elevation of a vacuum cleaner embodying my new design;

FIG. 2 is a rear view in elevation of FIG. 1;

FIG. 3 is a top plan view of FIG. 1;

FIG. 4 is an elevational view taken from the left of FIG. 1;

FIG. 5 is an elevational view taken from the right of FIG. 1; and

FIG. 6 is a bottom plan view of FIG. 4.

I claim:

The ornamental design for a vacuum cleaner, as shown.
